UNITED STATES PATENT OFFICE.

WILLIAM E. JOSLIN, OF SARCOXIE, MISSOURI.

POST OR STAKE PULLER.

Application filed October 22, 1925. Serial No. 64,218.

To all whom it may concern:

Be it known that I, WILLIAM E. JOSLIN, a citizen of the United States, residing at Sarcoxie, in the county of Jasper and State 5 of Missouri, have invented certain new and useful Improvements in Post or Stake Pullers; and I do hereby declare the following to be a full, clear, and exact description of the invention, such as will enable others 10 skilled in the art to which it appertains to make and use the same.

The invention relates to means for pulling posts or stakes or the like out of the ground, and has for its principal object the provision 15 of a transportable frame having a wheeled axle located adjacent to one of its ends to act as a fulcrum for the frame that serves as a lever for pulling the posts or stakes and provided with means for engaging the post 20 or stake that is to be pulled.

A further object of the invention is the provision of clamping arms pivotally secured to the frame aforesaid and provided with means for adjusting the position of the 25 arms into and out of engaging position, the controlling means being adjacent the end of the frame remote from the fulcrum axle heretofore described for convenient control of the clamping arms by the operator of the 30 device.

A further object of the invention is the provision of clamping jaws mounted on the clamping arms and adapted to engage the post or stake, said clamping jaws being 35 rotatably mounted on the arms and under the control of the operator so that the post or stake may be canted to prevent binding in the ground while being removed.

The construction and operation of the invention as well as its advantages will be described in detail hereinafter, and the construction will be found illustrated in the accompanying drawings in which

Figure 1 is a top plan view of the improved post or stake puller,

Figure 2, a side view,

Figure 3, a longitudinal sectional view on a plane indicated by the line 3—3 of Figure 1,

Figure 4, a transverse sectional view on a plane indicated by the line 4—4 of Figure 2,

Figure 5, a detail sectional view on a plane indicated by the line 5—5 of Figure 55 3, and

Figure 6, a detail sectional view on a

plane indicated by the line 6—6 of Figure 4.

In the drawings similar reference characters will be used to designate corresponding parts throughout the several views. 60

The improved post or stake puller has a frame comprising side beams 1, across beam 2, and a brace beam 3 adjacent to one of the ends of the beams 1, while adjacent to the other ends of the beams is secured an axle 4 on which are journaled wheels 5, said wheeled axle admitting of ready transportation of the device, and also serving as a fulcrum for the frame, and the post or stake 65 engaging parts to be hereinafter described. 70

6 indicates two clamping arms pivotally engaging brackets 7 secured to cross beam 2 at one end thereof, while the free ends of the arms 6 rest upon the axle 4 and extend as shown, a short distance in front of the 75 axle. Rod 8 is slidably mounted in cross beam 2 and is connected with each of the clamping arms 6 by means of plates 9. 10 is a lever fulcrumed on bracket 11 supported on cross beam 2 and brace beam 3 and having a slot 12 therein to receive a pin 13 on the rod 8. It will be apparent that by actuating the rod 8 longitudinally that the clamping arms 6 will be moved toward or 80 from one another. Bracket 11 is furnished 85

with a segmental rack 14, and the lever 10 is furnished with a detent and thumb latch of standard construction as indicated at 15 to hold the lever 10 in adjusted position. 16 are spring arms secured to the outer 90 sides of clamping arms 6 and engaging side beams 1, and normally tending to move said clamping arms 6 toward one another.

The clamping jaw to engage the post or stake is rotatably mounted in the free end of each of the clamping arms 6 and comprises a clamping rod 17 with a stem 18 journaled in the arms 6 and having its outer face roughened or corrugated as shown at 19. 20 indicates a crank arm secured to rotate with stem 18, and has pivotally secured thereto a rod 21 that is pivotally secured to a crank arm 22 secured to rotate with a shaft 23 journaled as shown at 24 on the rear end of side beams 1. 25 is a crank 105 handle secured to shaft 23 and designed to rotate the shaft to rotate the clamping jaws 17.

In operation it will be apparent that the wheeled frame is moved into position so that 110 the clamping jaws 17 may be positioned on opposite sides of the post or stake to be re-

moved. The clamping arms 6 are then adjusted by means of lever 10, rod 8 and links 9 to cause the clamping jaws 17 to securely engage the post or stake adjacent to the ground. The rear end of the frame is then pressed downwardly and the post will be lifted from the ground. Should the post cant so as to bind against the walls of the hole out of which the post is being removed, it will be apparent that the canting of the post may be corrected by adjustment of the jaws 17 by movement of the shaft 23 through the instrumentality of the hand lever 25 to prevent the binding action and permit expeditious removal of the post or stake. As hereinbefore stated the wheeled axle 4 serves as a fulcrum for the frame that is to be used as a lever for removing the post, and said wheeled axle also serves to permit easy transportation of the device into location for operation on the post or stake to be removed.

What is claimed is:—

1. In a post puller, a frame, a wheeled axle supporting said frame and located adjacent to one end thereof and serving as a fulcrum for the frame, arms pivotally mounted

on said frame, jaws rotatably mounted on said arms, means to move the free ends of said arms towards and away from one another, and means to rotate said jaws. 30

2. A post puller comprising a frame, a wheeled axle supporting said frame and located adjacent to one end thereof and serving as a fulcrum therefor, arms pivotally secured at one of their ends to the frame and adapted to engage a post, a rod slidably mounted on the frame, links pivotally connecting said arms and rod, and means to adjust the rod to move said arms into and 35 out of engaging position. 40

3. A post puller comprising a frame, a wheeled axle supporting said frame and located adjacent to one end thereof and serving as a fulcrum therefor, arms pivotally secured at one of their ends to the frame and adapted to engage a post, means to adjust the position of said arms, clamping jaws rotatably mounted on said arms, a shaft journaled on the frame, and means connecting 45 50 said shaft and the clamping jaws to rotate the latter.

In testimony whereof I affix my signature.
WILLIAM E. JOSLIN.
